STOKER

Samuel G. Jones, Princess Anne County, Va., assignor to Berkley Machine Works and Foundry Company, Inc., Norfolk, Va., a corporation of Virginia

Application October 2, 1939, Serial No. 297,427

5 Claims. (Cl. 83—52)

This invention relates to stokers for automatically feeding coal to a fire, and more particularly to means for breaking up the coal into smaller pieces within the stoker.

5 In locomotive stokers, for example, a trough is mounted on a locomotive tender below an opening in its coal bin for receiving coal therefrom. The vertical front wall of the trough is provided with an opening from which a conduit extends 10 forwardly to the fire box of the locomotive. A conveyor screw is rotatably mounted in the trough and extends into the conduit for moving the coal out of the trough and through the conduit to the fire box. Due to the fact that much of the coal may be in pieces too 15 large to pass into the conduit it is customary practice to mount what is known as a coal crusher in the trough at the entrance to the conduit. This crusher usually takes the form of 20 a plurality of sharp projections projecting toward the rear end of the trough and arranged in a semi-circle around the upper half of the conveyor screw. Such crushers have several disadvantages. One is that they crush or grind 25 the coal into particles which are so small that a large proportion of them may be carried out of the stack of the locomotive by the draft without burning. Another difficulty is that the crusher interferes with feeding of the coal because it 30 knocks the pieces around in the trough to such an extent as to cause them to surge violently or boil at the entrance to the conduit instead of passing into it in an orderly manner. A further disadvantage lies in the fact that the crusher 35 is likely to be torn loose from the trough.

It is among the objects of this invention to provide a stoker crusher of simple and inexpensive construction, which is durable and exceptionally efficient in operation, which does not 40 pulverize the coal, which does not cause the coal to boil around it, and with which there is no danger of its being forced out of place.

In accordance with this invention the crusher 45 has a body portion provided at one end with an opening for receiving the conveyor screw and extending rearwardly and outwardly over the screw. The inside of the crusher is provided with one or more arcuate shoulders encircling the upper portion of the screw and preferably disposed in planes inclined to the axis of the screw to give the effect of a screw thread as the coal 50 is forced into the crusher by the conveyor screw. The thread of the conveyor screw preferably increases in diameter from the rear end of the 55 crusher toward its front end so as to produce a

shearing action in cooperation with the arcuate edges of the crusher's shoulders. To securely hold the crusher in place the tubular conduit that extends forward from the opening in the front wall of the trough has an extension projecting 5 back into the trough a short distance. This extension is provided with one or more shoulders that are engaged by cooperating projections on the crusher in order to relieve the bolts that connect the crusher to the front wall of the trough 10 from the torsional strain exerted by the crusher.

The preferred embodiment of the invention is illustrated in the accompanying drawings in which Fig. 1 is a fragmentary plan view of a locomotive stoker showing its trough with my 15 crusher mounted therein; Fig. 2 is a side view thereof partly broken away to show the crusher in vertical section; Fig. 3 is an enlarged vertical section of trough and crusher taken on the line III—III of Fig. 1; Fig. 4 is a view looking forward into the crusher; and Fig. 5 is a bottom view of the crusher.

Referring to Figs. 1 and 2 of the drawings, a locomotive stoker conveyor trough 1 is adapted to be mounted on a locomotive tender (not shown) in the usual way below its coal bin in order to receive coal therefrom. The trough carries a pair of wheels or rollers 2 that are guided on tracks on the tender in order to permit the trough to move relative to the tender to compensate for the relative movement between tender and locomotive. The front wall 3 of the trough is provided with an opening 4 from which a sleeve 6 projects forward for removably receiving the rear end portion of a tubular conduit 7 35 that extends forward to the locomotive. To detachably connect the tubular member to the trough so that either can be readily removed and replaced when worn, the front end of the sleeve is provided with a peripheral flange 8 to 40 which a similar flange 9 on the tube is bolted.

Coal is fed forward along the trough and through tubular conduit 7 by means of a conveyor screw 11 rotated by a small steam engine (not shown) 45 preferably mounted on the locomotive. The engine is connected to the rear end of the screw through suitable telescopically and universally connected shafts 12 (Fig. 2) that drive a speed-reducing gear unit 13 mounted in back of the trough where it is operably connected to the rear 50 end of the screw.

It is a feature of this invention that large pieces of coal in the trough are broken into smaller pieces so that the conveyor screw can carry them 55 forward into the tubular conduit. This is done by 55

means of a crusher which does not pulverize the coal and which does not cause it to boil in the trough at the entrance to the conduit. Accordingly, the crusher 16 is a roughly semi-circular casting that overlies the upper portion of the screw. The front end of the crusher is connected to the front wall of the trough in a manner about to be described, and the crusher extends rearwardly and flares outwardly away from the screw 10 similar to a funnel. In order to crush coal effectively without requiring a great deal of power the inner surface of the crusher is provided with a plurality of concentric shoulders 17 partially encircling the screw. Each shoulder has an arcuate 15 lower surface and a substantially vertical lateral surface meeting the lower surface at substantially a right angle to form an arcuate cutting edge for the coal. As the coal is forced against these shoulders by the conveyor screw, it is broken into pieces small enough to pass into the conduit. As shown in Figs. 1 and 5, the shoulders 20 are preferably disposed in planes inclined to the axis of the screw to produce a thread effect that guides the coal into and through the crusher as the coal is moved ahead by the screw. Due to this and the lack of projecting fingers, the coal does not boil around in the trough and crusher and become pulverized, but passes directly 25 through the crusher in an orderly manner in relatively large pieces. Once a piece of coal enters the crusher there is nothing to knock it back out again.

Another feature of this invention is that the screw thread increases in diameter from the rear 30 end of the crusher toward its front end, as shown in Figs. 1 and 2, so that it exerts a shearing action on coal between the periphery of the thread and the edges of the shoulders. The result is that 35 less power is required for the coal crushing operation.

A still further feature resides in the manner in which the crusher is fastened in place in the trough. The rear end of tubular conduit 1 projects into the trough a sort distance and its 40 lower half is cut away to form a pair of downwardly facing shoulders 21, as shown in Figs. 2 and 3. The front portion of the crusher rests on this tubular extension and has inwardly projecting lower portions forming shoulders 22 that 45 extend under and engage the tube shoulders for preventing the crusher from being rotated or moved in the transverse plane of the tube. To hold the crusher on the tube extension it is provided at opposite sides with lugs 23 from 50 which bolts 24 extend through the front wall of the trough. With this construction the bolts merely hold the crusher on the tube, and the tube itself takes the torsional strains exerted by the crusher which might otherwise shear off 55 the bolts. There is thus no danger of the crusher being torn loose from its mounting.

According to the provisions of the patent statutes, I have explained the principle and mode of operation of my invention and have 60 illustrated and described what I now consider to represent its best embodiment. However, I desire to have it understood that, within the scope of the appended claims, the invention may be practiced otherwise than as specifically illustrated and described.

I claim:

1. In a stoker, a trough provided at its front end with an opening for receiving a conveyor screw, a tube extending forward from said opening and having an extension projecting into the trough provided with a shoulder, a crusher overlying at least the upper portion of said extension and provided with a shoulder engaging said tube shoulder to lock the crusher against movement transversely of the tube, and means for holding the crusher against movement axially of the tube.

2. In a stoker, a trough provided at its front end with an opening for receiving a conveyor screw, a tube extending forward from said opening and having an extension projecting into the trough, the lower portion of said extension being cut away to provide shoulders, a crusher mounted on said extension and provided with inwardly projecting portions engaging said shoulders to lock the crusher against movement in the transverse plane of said tube, and means for locking the crusher against movement axially of the tube.

3. In a stoker, a trough having a front wall 25 provided with an opening therethrough for receiving a conveyor screw, a tube extending forward from said opening and having an extension projecting into the trough, the lower portion of said extension being cut away to provide 30 shoulders substantially perpendicular to said front wall, a crusher mounted on said extension and having inwardly projecting lower edges engaging said shoulders for locking the crusher against movement transversely of said tube, and 35 means for fastening the crusher to said front wall to prevent it from moving axially of the tube.

4. In a stoker, a trough having a front wall 40 provided with an opening therethrough for receiving a conveyor screw, a tube extending forward from said opening and having an extension projecting into the trough, the lower portion of said extension being cut away to provide 45 shoulders substantially perpendicular to said front wall, a crusher mounted on said extension and extending rearwardly over the screw and flaring outwardly therefrom, the inside of the crusher being provided with an arcuate shoulder 50 extending transversely of the trough, the lower edges of the crusher projecting inwardly and engaging said tube shoulders for locking the crusher against movement transversely of said tube, and means for fastening the crusher to said front wall to prevent it from moving axially 55 of the tube.

5. In a stoker, a trough provided at its front end with an opening for receiving a conveyor screw, a tube extending forward from said opening and having an extension projecting into the trough provided with a substantially horizontal shoulder, a crusher engaging at least the upper portion of said extension and provided 60 with a substantially horizontal shoulder engaging said tube shoulder to lock the crusher against movement transversely of the tube, and means holding the crusher against movement axially of the tube.

SAMUEL G. JONES. 70
